UNITED STATES PATENT OFFICE.

WILLIAM JAMES DRAY, OF NEW YORK, N. Y.

GRATE-CLEANING DEVICE.

1,318,852.

Specification of Letters Patent.

Patented Oct. 14, 1919.

Application filed July 29, 1918. Serial No. 247,217.

To all whom it may concern:

Be it known that I, WILLIAM JAMES DRAY, a subject of Great Britain, and a resident of the borough of Manhattan, in the county, 5 city, and State of New York, have invented certain new and useful Improvements in Grate-Cleaning Devices, of which the following is a specification.

This invention relates generally to means 10 for cleaning grates in coal-burning apparatuses, and it more especially appertains to mechanical appliances for removing ashes, clinkers and other refuse, from the stationary grate-bars in marine boiler furnaces.

One of the objects of the invention is to produce an improved appliance of the nature set forth that can be readily applied to existing furnaces, as well as put into 20 new ones, and in either case may be depended on to keep the fires bright by opportunely liberating the grates from an undue accumulation of ashes, such as would cause thereon harmful aggregations and 25 crustations.

Another object is the production of an effective appliance of the type mentioned which shall be simple to operate and capable of being actuated with a moderate effort, 30 tending to preserve both the health and strength of the furnace attendants by relieving them of the arduous task of wielding the slow and ponderous hand-operated cleaning implements which they have here- 35 tofore been accustomed to manipulate.

A further object is to provide an openly 40 designed appliance of the character described which shall insure perfect combustion of the fuel burning upon the grate of the furnace, thereby economizing on the quantity of coal used, as also on the labor required in the handling thereof, and meanwhile remaining in a relatively cool condition, due to its exposure to air currents passing 45 under the grate.

Still another object is the provision of a strong and durable appliance of the kind specified, which shall be comparatively low-priced, inexpensive to install, composed of 50 few parts, not liable to get out of order, and easily renovated in such portion thereof as may eventually be in need of renewal or repairs.

A still further object is so to apply the 55 invention to its intended purpose that a single appliance will suffice to clean a plu-

rality of grates, the latter being acted upon conjointly and simultaneously.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawings, wherein like parts are designated by the same reference characters throughout the several views.

In the said drawings:

Figure I is a top plan view of a cleaning device constructed in accordance with the present invention, as applied to plural grates of a marine boiler, a portion of the latter and its furnace appearing in section, and certain parts being omitted;

Fig. II is a side elevation of the appliance, with the boiler and furnace in section similarly to the preceding view, parts being broken away; and

Fig. III is a front end elevation of the same form of the appliance as is represented in Figs. I and II, with the shell of the boiler, furnace flue, and grate-bars in section.

In these views, the reference character A denotes a corrugated furnace flue, of a type commonly used for boilers, around which is a front head B, and an outer shell C. At the rear end of the flue A stands a bridge wall D, and at the front end is a dead plate E, laid horizontally within an extension F, of the furnace. Grates, composed each of a number of parallel bars G, are placed end to end in a longitudinal series diametrically within the flue, and are supported in horizontal position therein by means of transverse carriers H, secured to the flue at their respective extremities. The 100 grate-bars G are shown as being received and lodged in recesses provided therefor in the carriers H, but they may simply be formed with heads, as G', at the ends to keep them spaced the proper distance apart adjacent to one another. The several parts here enumerated are ordinarily found in the standard marine steam-generator, that is, the so-called Scotch marine boiler.

Below the grates G, on opposite sides of the flue A and part of the extension F thereof, is located an open trackway 1, which

may consist of a pair of rails extending approximately the full length of the flue and secured to the bottom portion of the latter by means of lugs 2. The tread of each rail 5 will be preferably rounded to prevent lodgment thereon of ashes dropping down through the interstices of the grates thereabove.

Upon the track 1 is mounted a truck made 10 of a length somewhat exceeding that of one of the grates G and comprising flanged or grooved wheels 3 and 4, that are arranged in pairs forward and rearward respectively, and are adapted to roll along the said rails 15 a sufficient distance to run under the plural grates in succession, alternately advancing or retreating with relation to the same. The paired wheels are journaled upon opposite ends 3^a and 4^a of cross-bars 5 and 20 6, which are tied together by means of distance pieces 7, and form therewith an open quadrilateral truck frame.

Attached to the cross-bars 5 and 6 of the said frame are raking elements 10, arranged 25 in transverse rows at the opposite ends of the frame, one row being located on each side of the middle carriers H that support the adjacent inner extremities of the pair or plurality of grates G. The elements 10 30 are in the nature of elongated teeth, which are made to project upwardly between the several bars composing the grates, and to follow closely the sides of the bars without touching the same, when the truck is moved 35 back and forth upon the pair of rails thereunder. Thus positioned, the forward and rearward rows of toothed elements 10 form together with the truck frame a double rake, which is inverted and in permanent engagement 40 with some part of each grate. It is understood that the upper ends of these raking elements, which extend upwardly above the surface of each grate-bar, will instantly loosen the ashes therefrom and cause 45 them to fall to the bottom of the flue A, constituting the ash-pit of the furnace. By occasionally reciprocating the rake along the grates, the ashes and hot cinders will not have time to fuse and no clinkers will be 50 formed. The reciprocation of the rake, it will be noted, operates to clean the pair or plurality of grates simultaneously. As the grates extend laterally beyond the opposite sides of the truck frame, owing to the circular configuration of the flue A, the outermost raking elements 10^a are not attached 55 directly to the cross-bars 5 and 6, but are carried instead by straps 11, fastened to the nearest elements 10 in their respective rows 60 and extending outwardly past the rails 1 to the adjoining side walls of the flue.

The drawings hereto annexed illustrate 65 one of the several ways in which the rake aforesaid can be reciprocated under the plural grates G to relieve them of ashes and

the like. In Figs. I, II and III, the means for moving the rake is shown as consisting of chains 14 and 15, respectively attached to the cross-bars 5 and 6 of the truck or frame. The upper forward chain 14 winds around 70 a wide-faced spool 16, to which it is fastened by one end, the other end thereof being secured to the front bar 5. The chain 15, connected at one end to the rear bar 6, runs over a sheave 17, and thence toward the 75 front, where its other end is anchored to the spool 16, but in a direction opposite to that of the first-named chain. The spool 16 and sheave 17 are mounted on shafts 18 and 19, journaled in the front and rear ends 80 of the rails 1, respectively.

Upon the near end of the forward shaft 18, as viewed in Figs. I and II, is fastened a worm-gear 22, with which a worm 23 has meshing engagement. The latter is driven 85 by a forwardly-projecting spindle 25, fitted in suitable bearings provided therefor in a bracket 24, secured exteriorly upon the furnace extension F. This bracket also affords a bearing for the outboard portion of the 90 shaft 18, as best seen in Fig. III. The spindle 25 can be easily rotated by means of a crank 26, provided for its manual operation. Obviously, however, the same spindle may have its motive force applied there- 95 to from an auxiliary engine or motor. As will be readily perceived, when the worm 23 is turned in one direction, the gear 22 causes the spool 16 to wind up the chain 14 and draw the truck forward, while at 100 the same time it lets out the chain 15. Reversely, the chain 15 will wind around the spool, and the chain 16 be paid out, in which case the truck is pulled rearward. The gear- 105 ing is such that it will maintain the thereto related parts in any given position. Due to this arrangement, the truck and toothed elements constituting the double rake may be stationed anywhere under and along the plural grates, whether intentionally or otherwise, and can be relied on to perform thoroughly the grate cleaning operation, whenever called into use. 110

From the foregoing it will be seen that the rake is effectively reciprocated to clean 115 the plurality of grates, whenever the spindle 25 is rotated, either manually with the aid of the crank 26, or mechanically through the medium of some suitable power connection. The rotation of the spindle 25 sets 120 in motion the worm 23 that meshes with the worm-gear 22, and the latter in turn revolves the shaft 18. The spool 16 carried by this shaft, will transmit the movement to the combined truck and rake, the spool alternately winding and unwinding the chains 14 and 15, which serve to move the truck and rake back and forth in the manner already pointed out. It is understood, of course, that the spindle 25 is rotated in one 125 130

direction to pull the truck and rake forward, and in the opposite direction to draw the same rearward.

While a certain preferred embodiment of this device has been shown and described, it will be understood that changes in the form, arrangements, proportions and details thereof may be made, without departing from the scope of the invention as defined 10 by the appended claims.

Having described my invention what I desire to secure by Letters Patent and claim, is:—

1. A cleaning appliance for a grate, including a slideable rake normally engaged with the latter, a wheeled truck supported to roll beneath said grate in position to carry said rake, and means including a gear locked chain drive for temporarily setting 20 said truck in any chosen position.

2. The combination with a plurality of grates sequentially arranged in a longitudinal direction, of a reciprocable wheeled truck of greater length than either one of 25 said grates, raking elements projecting between individual bars of each grate from the ends of said truck, and chains attached to said ends for reciprocating the truck with said elements.

3. The combination with plural grates and supporting means therefor transversely arranged at their adjoining extremities, of a wheeled truck carrying substantially parallel series of raking elements respectively located on opposite sides of said supporting means, chain connections adapted to reciprocate said series of elements simultaneously in either direction, and operating mechanism common to said connections.

4. The combination with a plurality of grates following each other in longitudinal arrangement, of toothed elements projecting in rows at predetermined distances between bars of the forward and rearward grates respectively, a wheeled truck carrying said rows of elements and supported to roll beneath said grates, chains attached to the ends of said truck for drawing it with said rows of elements back and forth together, each through its respective grate, and a drum adapted alternately to wind one and unwind the other of said chains.

5. The combination with a grate, of an inverted rake normally engaging the same, a wheeled truck carrying said rake, rotatable elements including a drum and a sheave located respectively forward and rearward.

of said grate at opposite ends thereof, flexible connections attached to said truck and said drum, one of said connections passing over said sheave, and means for setting the 60 drum in rotation.

6. The combination with a grate, of a vehicular frame thereunder, toothed elements projecting in substantially parallel lines between bars of said grate from said frame, 65 oppositely disposed flexible connections adapted alternately to exert a drawing action upon the frame endwise thereof, and rotatable members over which said connections are passed, one of said members serving as an idler for one connection, the other member having both connections attached thereto so as to wind and unwind the same in opposite directions.

7. The combination with a grate, of a rake 75 engaging the same from the under side thereof, a wheeled truck carrying said rake, chains attached to the ends of said truck adapted to reciprocate the rake forward and rearward in a longitudinal direction, a drum to which the opposite ends of said chains are anchored so as to be alternately wound and unwound thereon, and gearing connected with said drum serving to stay the truck with the rake relatively to said grate 85 at any desired point therealong.

8. The combination with a grate, of a raking device movable thereunder, chains attached to the ends of said device, a drum arranged to wind and unwind said chains, 90 a gear capable of actuating said drum alternately in opposite directions, and a worm in engagement with said gear adapted to operate the drum so as to cause the chains to move the device and subsequently hold it 95 in a predetermined position.

9. The combination with a plurality of grates placed in sequence in a longitudinal direction, a trackway laid thereunder, a vehicular frame mounted so as to roll along 100 said trackway, toothed elements carried by said frame in permanent engagement with bars of said grates, chains attached to the ends of the frame, a drum and a sheave over which said chains are passed, shafts 105 for the latter named parts carried by the opposite extremities of the trackway, and gearing located to one side thereof adapted to wind and unwind the chains by alternate rotation of the drum in opposite directions.

WILLIAM JAMES DRAY.
